UNITED STATES PATENT OFFICE.

DAVID DUNN, OF PHILADELPHIA, PENNSYLVANIA.

MILK-BOTTLE SUPPORT.

1,378,403.

Specification of Letters Patent. Patented May 17, 1921.

Application filed April 17, 1920. Serial No. 374,538.

To all whom it may concern:

Be it known that I, DAVID DUNN, a citizen of the United States, residing in the city and county of Philadelphia, State of Pennsylvania, have invented a new and useful Milk-Bottle Support, of which the following is a specification.

My invention consists of a holder for a milk bottle which is adapted to lock the latter, and prevent abstraction of the same from without a room or apartment and guard the mouth of the bottle so that it is removed from being reached by flies and other insects, and licked by dogs or cats, as will be hereinafter set forth.

The invention is satisfactorily illustrated in the accompanying drawing, but the important instrumentalities thereof may be varied, and so it is to be understood that the invention is not limited to the specific details shown and described, as long as they are within the spirit or scope of the claims.

Figure 1 represents a perspective view of a holder for a bottle embodying my invention.

Fig. 2 represents a longitudinal vertical section thereof.

Fig. 3 represents a bottom plan view thereof.

Fig. 4 represents a rear view thereof partly broken away.

Fig. 5 represents a perspective view of a detached member of the device.

Similar numerals of reference indicate corresponding parts in the figures.

Referring to the drawings.

1 designates a hood consisting of a hollow body closed on its top, sides and front, and having in its bottom the opening 2 through which the neck of a bottle may be introduced into the interior of the hood. The back wall of the hood is formed with the opening 3 which provides for lightness of said wall and consequently of the hood.

45 In the lower portion of said back wall is the passage 4 which extends horizontally across said wall and is adapted to receive the resilient or spring bottle-holding plate or flap 5 which having its rear portion seated in said passage is adapted to occupy the hood 1 above the bottom of the latter and to be raised therefrom by the insertion of the mouth and consequently of the neck of a bottle upwardly into the hood, as will be hereinafter more fully explained.

The forward end of said flap is cut away

forming the recess 6 which is adapted to be above a portion of the opening 2 in the bottom of the hood, the front portion of said flap projecting somewhat forward from what may be termed the rear wall of said opening, as most clearly shown in Figs. 2 and 3.

In order to retain the flap in position its rear end has angularly formed with it or otherwise connected therewith as an elbow the limb 7 whose edge portions are adapted to be seated in the recesses 7^x in the outer side of the rear wall of the hood, whereby said limb is flush with said outer side of said wall, as most clearly shown in Fig. 2.

Rising from the top of said rear wall of the hood is the flange 8 and depending from the bottom thereof is the flange 9 which flanges in the present case are integral with said wall.

10 designates a plate adapted to connect the hood with the jamb of a door, it being secured thereto by screws 11 or other suitable means. On the upper and lower ends of said plate 10 respectively are the transversely extending channelled members 12 which form runways adapted to receive freely the flanges 8 and 9 respectively of the hood and permit said flanges to slide to the right and left on said plate while also adapted to support the hood on the door jamb in normal position, it being noticed that the outer terminal of said plate has thereon the vertically extending wall 13 which is adapted to limit the motion of the hood in the present case to the left and prevent the disconnection of the hood from the plate in that direction, the hood then being in position exterior of the door to receive a bottle which is introduced thereinto by the distributor of the milk, but the other end of the plate is open so that the hood can be removed therefrom in the direction to the right, but as noticed in Fig. 1 the door 13^x closes said open end and so primarily prevents the removal of the bottle until the door is opened from within by an occupant of the house supplied with the milk.

The operation is as follows:

The hood is in position in Figs. 1 and 2 to receive a bottle which is outside of the door, as has been stated, it being noticed in Figs. 1 and 3 that a portion 14 of the front of the resilient flap 5 projects forward of the rear wall of the opening 2 in the bottom of the hood so that said portion is

the path of the mouth of the bottle in the normal condition of the device.

The distributor of the milk presents the mouth of the bottle upwardly through the opening 2 and raises the bottle whereby the flap 5 owing to its resiliency yields and flexes upwardly, thus allowing said mouth and consequently the neck of the bottle to pass through the opening 2 in the bottom 10 of the hood. When the flange of the neck of the bottle clears the wall of the recess 6 of said flap 5 the latter returns to normal position downwardly, and said wall of the recess springs under a part of said neck of 15 the bottle and interlocks therewith. Then the bottle is let go and so it lowers when another portion of said neck seats itself on the front stationary portion 15 of the bottom of the hood, and thus the neck of the 20 bottle is locked in opposite directions in the hood, and so prevented from abstraction exterior of the door or outside of a hall or apartment.

When the bottle is to be properly removed 25 from the hood the door 13^x is opened and the hood is then free to be disengaged from the plate 10 this being accomplished by sliding the hood in the present case to the right until it clears said plate and the runways.

30 The limb 7 of the flap 5 is now exposed and accessible and the bottle is grasped and the flap 5 drawn rearwardly through the passage 4 by said limb 7 as a handle, whereby said flap emerges rearwardly through 35 the passage 4 and consequently from the neck of the bottle and the opening 2 of the bottom of the hood is clear of said flap when the bottle may be removed from the hood downwardly through said opening and carried elsewhere.

40 The flap may now be returned into the hood and the latter restored to normal position on the plate 10 when the door is closed and the hood is held supported on said plate 45 10 as before, and consequently on the door jamb ready to receive another filled bottle.

In the flap 5 is the opening 16 which is 50 adapted to render the former more pliable and resilient so as to be raised easily by the introduction of the bottle and then spring downwardly quickly to engage the neck of the bottle beneath the flange thereof.

Having thus described my invention what I claim as new and desire to secure by Letters Patent, is:—

1. In a bottle holding device of the character stated, a hood adapted to be movably supported adjacent to a door, an elbow shaped member composed of a horizontally-

extending flexible flap having therein a recess to receive the neck of a bottle, and a vertically extending limb adapted to carry said flap, said limb being slidingly supported on a plate of said hood.

2. In a bottle holder of the character stated, a hood, a plate connectible with the jamb of a door, means on said plate and hood for detachable attachment of the latter with the former and sustaining said hood in operative position on said jamb, said hood having an opening in its bottom, and a horizontally extending slideable flap member in the hood adapted to close partly said opening, and a vertically extending limb with which said flap is connected as an elbow, said limb being adapted to be retained on the back wall of said hood, said wall having therethrough in its bottom a passage in which said flap member is movable.

3. In a bottle holder of the character stated, a hood, a plate connectible with the jamb of a door, means on said plate and hood for detachable attachment of the latter with the former and sustaining said hood in operative position on said jamb, said hood having an opening in its bottom, and a horizontally extending slideable resilient flap member in the hood adapted to close partly said opening, and a vertically extending limb with which said flap is connected as an elbow, said limb being adapted to be retained on the back wall of said hood, said wall having therethrough a passage in which said flap member is movable, and having in its rear face a recess in which said limb is adapted to be seated.

4. In a bottle holding device of the character stated, a plate adapted to be secured adjacent to a door as a support for the device, said plate being provided with runways on the upper and lower ends thereof, a hood having an open bottom and provided with flanges which are supportable on and laterally slideable in said runways, and a resilient horizontal flap in said hood, said flap having a recess therein for the engagement therewith of the neck of a bottle, the back plate of said hood having therein a passage to receive said flap, and said flap having a carrier consisting of a vertical limb extending angularly from said flap, and being movably attachable to a plate of the hood.

DAVID DUNN.
